CORONA DISCHARGE VOLTAGE
REGULATOR

Paul W. Stutsman, Needham, Mass., assignor to
Raytheon Manufacturing Company, Newton,
Mass., a corporation of Delaware

Application June 22, 1950, Serial No. 169,550

3 Claims. (Cl. 313—206)

1

This invention relates to cold-cathode gaseous electron-discharge devices, and more particularly to cold-cathode discharge devices which operate in the dark current region of the Townsend discharge curve.

It is well known that a gaseous discharge may be had in the dark current region of the Townsend curve, and this phenomena has been used to produce gaseous-discharge devices such as rectifiers wherein a sharp point acted as the cathode, and a large surface acted as the anode.

One of the major advantages of these devices is that no initiating discharge is necessary to start the device, and the starting voltage of the discharge is below or equal to the operating voltage of the device. On the other hand, when a discharge device is operated in or above the glow discharge region, an initiating discharge must first occur, the voltage of said initial discharge being higher than the operating voltage.

Attempts to produce voltage regulators which operated in the dark current or corona discharge region met with serious difficulty, since the range of currents in the dark current region was extremely limited, and hence voltage regulation could not be had over any substantial range without the device passing over to a glow discharge which would change the operating voltage thereof, thus nullifying any regulating effect of the device.

This invention discloses a method of constructing voltage regulators which will operate satisfactorily in the dark current or corona discharge region.

Briefly, the structure comprises a pair of concentric cylinders, the inner cylinder being the anode, and the outer cylinder being the cathode.

This invention further discloses that the range of currents in the dark current region may be greatly extended by the use of a particular gaseous medium. In general, the gaseous medium comprises a mixture of two or more gases, the major component of the gaseous mixture being a gas which does not produce substantial negative ions upon ionization thereof or, in other words, a gas which upon ionization produces an abundance of free electrons. This gas may be, for example, any of the inert gases, such as helium. A quantity of a gas which may be termed a contaminant is added wherein slow speed collisions of electrons with the molecules of said contaminant gas are substantially inelastic.

While it has been found that hydrogen works extremely well, the invention is not necessarily

limited thereto, since many other gases, such as nitrogen or the halogens, may be used.

This invention further discloses the use of glass end shields for the anode cylinder whereby undesirable end effects which would be deleterious to the regulating characteristic of the device are substantially reduced. These end effects are, in part, the result of deposits of cathode material which would occur on the mica spacers in the absence of the shields, thereby changing the effective path length from the anode to the cathode of the device.

Other and further advantages of this invention will be apparent as the description thereof progresses, reference being had to the accompanying drawing, wherein:

Fig. 1 illustrates a longitudinal, cross-sectional view of an electron-discharge device embodying this invention; and

Fig. 2 illustrates a transverse, cross-sectional view of the device shown in Fig. 1 taken along lines 2—2 of Fig. 1.

Referring now to Figs. 1 and 2, there is shown a glass envelope 10 substantially cylindrical in form. The lower end of envelope 10 is closed by a glass base member 11 sealed thereto. Extending through base member 11 is a plurality of lead-in members 12. Inside envelope 10, lead-in members 12 are attached to a cathode cylinder 13 which may be, for example, of nickel. Cylinder 13 extends substantially the entire length of the envelope 10, the upper and lower ends of cylinder 13 being covered by circular mica spacers 14 and 15, respectively. Circular mica spacers 14 and 15 engage the inner wall of envelope 10, and thus are rigidly positioned with respect to envelope 10.

Mica spacer 15 has apertures therein which receive the lead-in members 12, said lead-in members being attached, as by welding, to the lower end of cylinder 13. Extending through mica spacer 15 is a shield member 16 comprising a glass tube. The lower end of glass tube 16 which is below mica spacer 15 is sealed to an anode support wire 17 which is welded to a bushing 18 positioned inside an anode cylinder 19. The entire assembly of bushing 18 and anode cylinder 19 extends into glass tube 16 concentric thereto, and is spaced slightly from the inner walls thereof.

Anode cylinder 19 extends upward through mica spacer 14, the upper end thereof being surrounded by an upper shield member 20 comprising a glass tube similar to lower shield member 16. The upper end of anode cylinder 19 is at-

tached, as by welding, to a bushing 21 which, in turn, is welded to a lead-in member 22. Lead-in member 22 extends out the upper end of shield member 20, and is sealed thereto, and out through the upper end of envelope 10.

Lead-in member 22 is sealed to the upper end of envelope 10, as at 23, and is attached, for example, by soldering, to a contact cap 24 bonded to the upper end of envelope 10 in a well-known manner by a mastic compound 25.

Shield member 20 passes through mica spacer 15 and snugly fits in the aperture therein. A metal clamp 26 surrounds shield member 16 immediately below mica spacer 15. Metal clamp 26 is attached, as by welding, to a plurality of tabs 27 which extends through mica spacer 15, and is attached, as by welding, to cathode cylinder 13.

Similarly, immediately above mica spacer 14 is a clamp 28 surrounding shield member 20 and welded to a plurality of tabs 29 which extends through mica spacer 14, and is attached, as by welding, to cathode cylinder 13. Thus, it may be seen that anode cylinder 19 is rigidly held with respect to cathode cylinder 13 both longitudinally and transversely.

While any desired mixture of gases may be used in envelope 10, as was previously explained, it has been found that approximately twenty centimeters of helium and four to six millimeters of hydrogen produce a satisfactory mixture for a tube which will have a constant voltage drop of substantially seven hundred volts for currents up to fifty microamps. Good results have been obtained with total pressures varying from 15 to 22 centimeters of mercury.

While the operation of the mixture of gases in the tube is not completely clear, it is believed that the inert gas or helium produces a supply of free electrons due to collisions of a stray electron with helium molecules, said collisions producing additional electrons. This multiplying action continues until all the free electrons produced by the collision of the particular stray electron arrive at the anode, the positive ions remaining being attracted to the cathode to become neutralized.

However, if current becomes too strong, it is believed that the multiplying action initiated by adjacent stray electrons produces groups so large that adjacent groups interfere with each other, thus producing a random motion of electrons and electron temperature, and resulting in a breakdown to a glow discharge.

By the insertion of a small quantity of a gas, wherein slow speed collisions of electrons with the gas molecules are substantially inelastic, electrons from one group which tend to stray toward the electrons of the other group are, to a large extent, absorbed by inelastic collisions with the added gas, and thus the tendency to breakdown to a glow discharge is reduced. This extends the permissible current flow in the dark current region.

This completes the description of the invention

illustrated herein. However, many modifications thereof will be apparent to persons skilled in the art without departing from the spirit and scope of this invention. For example, any desired anode and cathode configuration could be used. In addition, any desired pressure of a gaseous medium could be used, dependent on the mixture of the gaseous medium and the regulating voltage desired.

Furthermore, the electrodes may be made of any desired material which does not react with the particular gases of the medium. For example, if one of the halogens were used in the gaseous medium, the electrodes would preferably be made of stainless steel or tantalum rather than nickel. Therefore, it is desired that this invention be not limited to the particular details of the species of the invention illustrated herein, except as defined by the appended claims.

What is claimed is:

1. An electron-discharge device comprising an envelope containing a cathode having a substantial electron-emitting surface, an anode surrounded by said cathode, said anode extending out beyond the ends of said cathode, dielectric shielding members covering the portions of said anodes which extend beyond the ends of said cathode and a gaseous medium comprising a free electron gas and a gas wherein slow speed collisions of electrons with the molecules of said gas are substantially inelastic.

2. An electron-discharge device comprising an envelope containing an anode cylinder, dielectric shielding members covering both ends of said anode cylinder, a cathode spaced from said anode and extending over portions of said shielding members, a portion of said anode cylinder between the ends thereof being exposed to said cathode, and a gaseous medium comprising helium containing a small quantity of hydrogen.

3. An electron-discharge device comprising an envelope containing an anode cylinder, shielding members covering both ends of said anode cylinder, a cathode spaced from said anode and coaxial therewith, a portion of said anode cylinder between the ends thereof being exposed to said cathode, and a gaseous medium comprising a free electron gas and a gas wherein slow speed collisions of electrons with the molecules of said gas are substantially inelastic.
